UNITED STATES PATENT OFFICE.

EDWARD F. RHOADES, OF PROVIDENCE, RHODE ISLAND, ASSIGNOR TO PROVIDENCE MACHINE WORKS, OF PROVIDENCE, RHODE ISLAND.

BATTERY-POST CONNECTER.

Application filed October 18, 1927. Serial No. 227,030.

My invention relates to improvements in battery post connecters wherein the same is particularly constructed and adapted for more effectively gripping the post of a conventional storage battery.

The binding posts of storage batteries frequently become corroded, and in this condition it is quite difficult to make the proper electrical connection with the types of battery clips now in use, the spring clip now being used, being generally not practical in most cases, because the spring tension thereof is not sufficient to cause the teeth thereof to bite through the corroded portion of the post, the main object of my invention being to remedy such a situation by providing a device which can more effectively be clamped to the binding post of a battery.

Another object resides in the particular means I have employed for actuating the jaw members of my connecter, to cause the same to effectively bite into the battery post.

Still another object resides in the particular construction of the jaw members for the purpose more fully set out in the following specification.

Other very novel objects and advantages of my improved connecter will be apparent as the same is better understood from the specification and claim to follow.

In the drawing:

Figure 1 is a side elevation of the connecter.

Fig. 2 is a sectional view taken substantially on the line 2—2 of Fig. 1.

Fig. 3 is a sectional view taken approximately on the line 3—3 of Fig. 1, and

Fig. 4 is a cross sectional view taken substantially on the line 4—4 of Fig. 1.

For a more detail description of my invention, I now refer to the drawings in which like numerals designate like parts of the same.

An elongated plate 1 is intermediately formed with a pair of spaced ear members 2. Adjacent one end portion of the plate 1, a set screw 3 is adapted to be threaded therein for clamping an electrical lead wire against the plate in a manner not shown in the drawing.

The opposite end of the plate 1 is provided with an offset jaw member 4 of substantially greater width than the width of the plate 1. The jaw 4 is longitudinally arcuate in shape and formed with a pair of rib members 5 at the longitudinal edges thereof.

These rib members are also of arcuate shape to conform with the contour of the binding posts to which they are to be clamped.

A complementary curved plate 6 is provided at its intermediate portion with an ear member 7. This ear member 7 is adapted to be disposed between the ear members 2 of the plate 1, while a pin 8 connects the same in hinged relation. One end of the curved plate 6 is formed with a head portion of greater thickness than the thickness of the curved plate 6. This head portion 9, has a threaded bore through which the threaded element 10 is adapted to feed.

The threaded end portion of the element is adapted for engagement in the inner surface of the plate 1, the opposite end of the threaded element being bent laterally as at 11, whereby a finger grip may be had thereon. The opposite end of the plate 6 is curved to provide a jaw of similar curvature to the jaw 4.

The jaw 12 is formed with a longitudinal rib 13 extending intermediate the edge portions thereof, as in a manner clearly shown in Fig. 2 of the drawing. The jaw 12 is also offset, in the same direction as the jaw 4, for the purpose which will be set out hereinafter.

Before applying my connecter to the posts of a storage battery, the threaded element 10 is fed outwardly, so that the jaw members 4 and 12 respectively may be expanded. In this expanded position, they are disposed around the battery post in a suitable position in respect thereto so that by tightening the threaded element 10, the jaw members 4 and 12 will be drawn together, thus causing the ribs 5 and 13 respectively, to bite effectively through any corrosion on the post to provide a perfect electrical connection therewith.

The more the threaded element 10 is threaded through the head 9 and against the plate 1, the greater will be the pressure of the jaw members 4 and 12 respectively in contact with the post.

As will be clearly seen in the drawings, the jaw portions of the respective plate members, are offset so that the connecter may be gripped in the hand, without the liability that the hand will come in contact with any part of the storage battery, which is usually unclean and undesirable to touch.

Having thus described my invention, what I claim as new is:—

In a connector for battery posts, a pair of pivotally connected angular shaped plates, said plates being curved at one of their adjacent ends to provide opposing jaws, ribs on the inner faces of the jaws, the opposite end of one of said plates being adapted to project beyond the end of the complementary plate, a binding post provided on said projecting end, and a threaded element threaded through one of said plates and adapted to seat against the complementary plate, whereby the jaw members may be contracted. 10

In testimony whereof I affix my signature.
EDWARD F. RHOADES.
